UNITED STATES PATENT OFFICE.

MARTIN CODY, OF NEW YORK, N. Y.

FIRE-ESCAPE.

SPECIFICATION forming part of Letters Patent No. 738,164, dated September 8, 1903.

Application filed December 20, 1902. Serial No. 135,992. (No model.)

To all whom it may concern:

Be it known that I, MARTIN CODY, a citizen of the United States, and a resident of the city of New York, borough of Manhattan, in the 5 county and State of New York, have invented a new and Improved Fire-Escape, of which the following is a full, clear, and exact description.

The invention relates to fire-escapes of the 10 portable spar and tower class; and its object is to provide a new and improved portable fire-escape which is simple and durable in construction, readily placed in position on a building, provided with a convenient descending means, especially serviceable for supporting women, children, invalids, and other persons, and arranged to insure a safe descent from any floor of the building to the sidewalk.

The invention consists of novel features 15 and parts and combinations of the same, as will be more fully described hereinafter and then pointed out in the claims.

A practical embodiment of the invention is represented in the accompanying drawings, 20 forming a part of this specification, in which similar characters of reference indicate corresponding parts in all the views.

Figure 1 is a perspective view of the improvement as applied. Fig. 2 is a transverse 25 section of the same on the line 2 2 of Fig. 4. Fig. 3 is a plan view of the same. Fig. 4 is a front elevation of the same. Fig. 5 is an enlarged transverse section of the fastening device for securing the window cross-beam to 30 the support, and Fig. 6 is a sectional side elevation of a modified form of the stay-rod for the support of the upper end of the ladder.

On the upper end of a ladder A is secured a transversely-extending support B, carrying 40 on its free end a cross-beam C, adapted to rest against the side of a building D, as shown in the drawings, and on the said support B is secured a depending hook E, on which is suspended the upper sheave F' of a rope and 45 tackle F of any approved construction, and carrying at its lower sheave F² a basket G, so that the basket extends between the ladder and the face of the building to allow convenient raising and lowering of the basket 50 by the operator actuating a windlass H, held on the lower end of one of the side beams of the ladder, on which windlass winds and un-

winds the rope F³ of the rope and tackle F. The cross-beam C, above mentioned, is of sufficient length to extend across a window 55 of the building, as plainly indicated in Figs. 1, 3, and 4, so that the basket G can be raised to any one of the windows in a vertical line to enable the persons to step readily from the window into the basket. Now by the operator 60 manipulating the windlass H the basket with the persons therein can be readily lowered to the sidewalk and when emptied is again ready for hoisting and taking down another load of persons desiring to escape from 65 the building in case of fire. The basket G is very roomy, so that a large number of persons can be accommodated at a time, and, if necessary, a fireman or other person can be raised in the basket from the sidewalk up to a window 70 to assist in the escape of persons from the building and also to save property, if desired. The support B is mortised in the upper ends of the side beams of the ladder A, and a bolt I is passed through the support and the beams 75 of the ladder to securely fasten the support in position on the upper ends of the side beams. In order to give the desired strength to the support B, one of the upper rungs of the ladder is connected by braces J with the 80 free end of the support B, each brace J being preferably made in sections connected with each other by a turnbuckle, as plainly indicated in the drawings, to allow of adjusting the braces to insure proper bracing of the 85 support from the ladder. Stay-rods K connect the upper rung of the ladder with the outer end of the support B to increase the supporting strength of the support B. The stay-rods K may be provided with extensions 90 K², engaging another rung of the ladder, as plainly illustrated in Fig. 6. The cross-beam C is fastened by bolts C' to U-shaped clips B', attached by bolts B² to the free end of the support B, as plainly indicated in Fig. 5, and 95 by this arrangement cross-beams C of different lengths may be employed to extend across windows of more than ordinary width.

From the foregoing it will be seen that the fire-escape is very simple and durable in construction, and as it is portable it can be readily moved along a burning building to the different windows to allow of rescuing persons from every part of the building. The 100

ladder A is of sufficient length to bring the support B close to the roof of the building to allow of raising the basket G to the windows at the uppermost floor.

5 Having thus described my invention, I claim as new and desire to secure by Letters Patent—

1. A portable fire-escape provided with a ladder, a hoisting and lowering device, provided with a windlass on the lower end of the ladder, an abutting support from which the said device is suspended, the support being mortised to receive the upper ends of the side beams of the ladder, a transverse bolt passing through said support and upper ends of the side beams of the ladder, stay-rods connecting the upper rung of the ladder with the outer end of the support, braces connecting an upper rung with the support, said braces being provided with turnbuckles, U-shaped clips attached to the inner end of said support, and a transverse bar secured to said end through the medium of said clips, the ends of said transverse bar projecting beyond the sides of the support, as specified and for the purpose set forth.
2. A portable fire-escape provided with a

ladder, an abutting support secured on the upper end of the ladder, U-shaped clips embracing the inner end of said support and secured thereto, and a transverse bar secured to said inner end of the support through the medium of said clips, the ends of said transverse bar projecting beyond the sides of the support, as specified and for the purpose set 35 forth.

3. A portable fire-escape provided with a ladder, a hoisting-and-lowering device, an abutting support from which the said device is suspended, the support being mortised in 40 the upper ends of the side beams of the ladder, braces connecting an upper rung with the support, stay-rods connecting the upper rung of the ladder with the outer end of the support, and a cross-beam bolted to the in- 45 ner free end of the support, as set forth.

In testimony whereof I have signed my name to this specification in the presence of two subscribing witnesses.

MARTIN CODY.
